(57) **CLAIM**

The ornamental design for an electrical socket, shown and described.

DESCRIPTION

FIG. 1 is a perspective view of an electric socket, with an incorporated LED window, showing our new design;

FIG. 2 is a top plan view thereof;

FIG. 3 is a bottom plan view thereof;

FIG. 4 is a first side elevation view thereof;

FIG. 5 is a second side elevation view thereof;

FIG. 6 is a third side elevation view thereof; and,

FIG. 7 is a fourth side elevation view thereof.

Those elements shown in phantom lines in the drawings are for environmental purposes only and form no part of the claimed invention.
